UNITED STATES PATENT OFFICE.

GOLDWIN S. SPRAGUE, OF NEWTON, MASSACHUSETTS.

SNOW-SHOE.

1,154,347.

Specification of Letters Patent. Patented Sept. 21, 1915.

Application filed January 18, 1915. Serial No. 2,810.

To all whom it may concern:

Be it known that I, GOLDWIN S. SPRAGUE, a citizen of the United States, residing at Newton, county of Middlesex, State of Massachusetts, have invented an Improvement in Snow-Shoes, of which the following description, in connection with the accompanying drawing, is a specification, like characters on the drawing representing like parts.

10 This invention relates to the construction of snow shoes particularly with reference to that part known as the foot binding.

The object of the invention is to provide a construction in which the toe cap shall be 15 pivotally mounted upon the toe cord without danger of slipping out of position laterally and in which the pivotal connections shall be rigidly secured in place against usage and yet be capable of separation for 20 purposes of renewal and repairs.

Another object of the invention is to enable the toe cap and the heel strap to be separately connected to the toe cord and at the same time brought into such relation as 25 to fit snugly around and against the foot.

Another feature of the invention consists in the provision of ear plates or strips of leather overlying the vamp portion of the toe cap and secured at the edges thereto 30 whereby the foot is prevented from crowding the vamp over sidewise.

Another feature of the invention resides in the construction of the opposite edge portion of the toe cap each with a series of eyelets and a lacing whereby the vamp portion 35 may be fitted to and held in place upon the toe.

These and other objects of the invention will appear more fully from the accompanying 40 description and drawings and will be particularly pointed out in the claims.

Figure 1 is a plan view of a snow shoe embodying the preferred form of this invention; Fig. 2 is a cross section of a portion of the shoe shown in Fig. 1, taken on the line $x-x$; Fig. 3 is a perspective view of the bushing or that portion of the pivotal connection between the toe cap and toe cord which is secured to the latter.

50 This invention is applicable to any form of snow shoe and for convenience of illustration that form of snow shoe known as the "bear paw" is illustrated.

A snow shoe as is well known comprises 55 the wooden frame 1 which is made of various shapes and sizes, and the interwoven fill-

ing 2 of various designs and proportions filling the space inclosed by the frame. At the forward end of the shoe there is a strut or cross bar 3 forming a portion of the frame and known as the toe bar. Directly behind 60 this and extending across the shoe is a twisted cord of rawhide 4 known as the toe cord. There is thus left between the two a space 5 known as the toe hole in which the 65 toe of the wearer moves in walking.

The foot of the wearer is held in place on the shoe by the foot binding which in this invention comprises a toe cap and a heel strap, each pivoted independently of the 70 other to the cord 4. This is very desirable because according as the wearer is going up hill or down hill the strain is shifted from the one to the other and the independent connection of the toe cord enables the strain 75 thus to be shifted without bringing a strain upon the other part.

The toe cap and the heel strap are usually and preferably made of leather and that term will be used herein and in the claims 80 as descriptive of the material of these parts, but not as restrictive because the use of any other material if suitable does not affect in any way the nature or scope of the present invention.

The toe cap in the preferred form of this invention comprises a foot plate 6 of the shape shown in Fig. 1 somewhat wider at the rear and narrowing toward the front and of sufficient length properly to support the sole of the foot. It comprises 90 also a pair of similar complementary vamp plates 7 superposed at their outer edges upon the foot plate and provided at their free edges with metal eyelets 8 through 95 which a lacing or thong 9 is passed, and by means of which the vamp plates are snugly fitted over the toe of the wearer in such a manner as to allow the point of the toe to project into the toe hole to the required extent. These metal eyelets are important because in the use of rawhide and any other suitable material such material soon becomes soaked with water, and it is difficult to adjust the lacing, difficult 100 for it to be drawn through the holes, and the holes are liable to be torn out under the strain to which the toe cap is subjected in use. The metal eyelets take up 105 this strain and distribute it in such a manner that the permanency of the toe cap is assured and the ready adjustment of the

lacing is permitted at all times. The toe cap also comprises a pair of similar complementary plates 10 which are herein termed ear plates which are also made of rawhide 5 and are superposed upon the vamp plates at their edges. These ear plates overlie the vamp plates for a portion of their width, but are not connected thereto at their free edges. These ear plates reinforce the vamp 10 plates at the edges in such a manner that the sidewise thrust of the foot as when walking on a side hill or when the foot is thrust sidewise, will not allow the foot to move over the rivets and distort the toe 15 cap.

The three plates forming the toe cap are secured together in superposed relation as shown in Fig. 2 by a plurality of metal rivets 11. These rivets hold the plates 20 firmly in place and are peculiarly adaptable to secure their holding function when the rawhide is wet and to withstand the strain placed upon them by the twisting or sidewise thrust of the foot.

The toe cap is secured to the toe cord so as to provide the necessary pivotal movement by a connection formed of metallic parts and comprising a bushing, shown detached in Fig. 3, surrounding the toe cord 30 and firmly held in place in the filling and a staple removably secured in place in the toe cap. One of these connections is located at each side as shown in Fig. 1. This not only provides for perfect freedom of 35 pivotal movement, but also prevents wear on the toe cord and filling of the snow shoe. The bushing comprises a hollow bearing cylinder 12 having an arm 13 rigid or integral therewith at the outer end and a flange 14 at the inner end. The bearing cylinder 12 is slipped over the toe cord at the time the filling is interwoven and the arm 13 lies up and against the cord 15 extending from the toe bar 3 to the toe cord 40 and is shaped to conform to the cord 15, and is held in place by the winding 16. The result is that this bushing becomes a firm and rigid part of the filling. The staple 17 is threaded at each end and is passed up 45 surrounding the cylinder 12 and its ends carried through the superimposed plates of the toe cap, and also through a small metal plate 18 superimposed on the ear plate. The ends of the staple are threaded. Nuts 50 19 are then screwed on the threaded ends of the staples until the parts are in the right adjustment to provide a free pivoting of the toe cap and then the threaded projecting ends of the staple are hammered or burred 55 down so as to prevent the nuts from coming off, but allowing them to be removed with a wrench when necessary for repair or replacement of the toe cap. The flange 14 on each bushing prevents the movement 60 of the staple too far toward the center of

the shoe while the arm 13 limits its movement in the opposite direction so that while sufficient freedom of movement is allowed to the toe cap it cannot when wet and under a heavy sidewise thrust move out of place 70 or shift at its edge too far toward the center of the shoe.

The metal parts which have been referred to particularly, the bushings and staples are made of suitable non-corrosive metal 75 such as brass or what is known as Newton metal.

The heel strap 20 which is made in two parts adjustably secured together by an ordinary fastening such as a buckle is pivotally secured at its ends to the toe cord at points independent of the toe cap so that the toe can pivot independently of the heel strap, and vice versa. This makes the strain on the two parts of the foot binding 80 independent of each other. But it is necessary for an efficient foot binding that the heel strap in its passage around the foot shall conform closely to the side of the foot, and to secure this result the toe cap at its 90 rear edge adjacent the foot of the wearer is slotted. This slot may be in either portion of the toe cap and is herein shown for convenience in the ear plate. Thus, it will be seen that the heel strap conforms to the 95 side of the foot of the wearer.

It will thus be seen that the various features of this invention described combine to produce a highly efficient form of foot binding for a snow shoe which will properly 100 take care of all the conditions attending such a shoe in use and the great strains to which it is subjected.

Having fully described my invention, what I claim as new and desire to secure by Letters Patent is:

1. In a snow shoe the combination of a pair of metal bushings mounted on the toe cord at each side of the toe hole and provided on their outer ends with arms by which they are secured to the filling and against rotation, and on their inner ends with flanges, a foot binding comprising a toe cap and a heel strap, metal staples surrounding each bushing having threaded ends 110 passing through the toe cap and a nut on each staple end whereby the toe cap is pivotally secured to the toe cord and sidewise movement thereof limited.

2. In a snow shoe the combination of a 120 pair of metal bushings mounted on the toe cord at each side of the toe hole and provided on their outer ends with arms by which they are secured to the filling and against rotation, and on their inner ends 125 with flanges, a foot binding comprising a toe cap and a heel strap, metal staples surrounding each bushing having threaded ends passing through the toe cap and a nut on each staple end, the said heel strap being se- 130

cured to the toe cord independently of the toe cap and then passed through apertures in the rear edge of the toe cap whereby the two parts of the foot binding are independently pivoted to the toe cord and the heel strap at the same time conforms to the foot of the wearer.

3. In a snow shoe foot binding a toe cap comprising a foot plate, vamp plates superimposed at their outer edges on the foot plates, ear plates superimposed at their outer edges on the vamp plates and overlying the outer portion of the vamp plates, and means for securing together the superimposed edges of the said plates.

4. In a snow shoe foot binding a toe cap comprising a foot plate, vamp plates superimposed at their outer edges on the foot plates, ear plates superimposed at their outer edges on the vamp plates and overlying the outer portion of the vamp plates, means for securing together the superimposed edges of the said plates, metal eyelets at the opposing free edges of the vamp plates, and a lacing for the eyelets.

5. In a snow shoe foot binding a toe cap comprising a foot plate, vamp plates superimposed at their outer edges on the foot plates, ear plates superimposed at their outer edges on the vamp plates and overlying the outer portion of the vamp plates, and metal

rivets passing through and securing said superimposed edges of the said plates.

6. In a snow shoe foot binding a foot plate, vamp plates superimposed at their outer edges on the foot plate, ear plates superimposed at their outer edges on the vamp plates and overlying the outer portion of the vamp plates, and each provided with an aperture at its rear edge, means for adjustably connecting the free edges of the vamp plates, means for pivotally securing the toe cap to the toe cord, a heel strap having its ends pivotally secured to the toe cord independently of the toe cap and passed through the apertures in the ear plates.

7. In a snow shoe foot binding a toe cap, a heel strap, the said toe cap and heel strap being pivotally connected independently of each other to the toe cord, and the said heel strap passed through apertures in the rear edge of that portion of the toe cap extending over the foot whereby the heel strap conforms to the shape of the side of the foot.

In testimony whereof, I have signed my name to this specification, in the presence of two subscribing witnesses.

GOLDWIN S. SPRAGUE.
